US0D1002915S

(12) **United States Design Patent** (10) **Patent No.:** **US D1,002,915 S**
(45) **Date of Patent:** **** Oct. 24, 2023**

(54) **LENS**

(71) Applicant: **Chen Wu**, Zhuhai (CN)

(72) Inventors: **Zhenghai Wang**, Zhuhai (CN);
Zhengyu Wang, Zhuhai (CN)

(73) Assignee: **Chen Wu**, Zhuhai (CN)

(**) Term: **15 Years**

(21) Appl. No.: **29/860,339**

(22) Filed: **Nov. 17, 2022**

(30) **Foreign Application Priority Data**

May 18, 2022 (EM) 009030018-0001
